UNITED STATES PATENT OFFICE.

ARTHUR HALE, OF NEW YORK, N. Y.

HEAD-COVERING.

1,057,825.

Specification of Letters Patent. Patented Apr. 1, 1913.

Application filed October 2, 1911. Serial No. 652,357.

To all whom it may concern:

Be it known that I, ARTHUR HALE, a citizen of the United States, residing at New York, in the county of New York and State of New York, have invented certain new and useful Improvements in Head-Coverings; and I do hereby declare the following to be a full, clear, and exact description of the invention, such as will enable others skilled in the art to which it appertains to make and use the same.

This invention relates to washable head gear, and especially to hats and caps, and has for its object to provide an article of this character which will permit the stiffening members to be readily withdrawn when the fabric, out of which the head covering is made, may be washed, and then the said stiffening members readily reinserted.

To these ends the invention consists in the novel details of construction and combinations of parts more fully hereinafter disclosed and particularly pointed out in the claim.

Referring to the accompanying drawings forming a part of this specification in which like numerals designate like parts in all the views:—Figure 1 is a view of a cap made in accordance with my invention; Fig. 2 is a sectional view of the parts shown in Fig. 1; Fig. 3 is an enlarged detail diagrammatic sectional view of a portion of the parts shown in Fig. 2.

1 represents a cap or other head covering made of any suitable material, but preferably made of washable fabric. 2 represents

the vizor of said cap, which is provided with the walls 3 and 4 secured around their edges at 5 to form an open mouth pocket 6, into which fits a stiffening member 7 such as a 40 crescent shaped piece of leather, leather-board or other material. The mouth 8, of the pocket 6, is left open so that the stiffening member 7 can be readily withdrawn or inserted at will.

9 and 10 represent fastening members by which the vizor 2 may be secured to the crown portion of the cap, when desired, in the usual manner.

It is obvious that those skilled in the art may vary the arrangement of parts and the details of construction without departing from the spirit of my invention, and therefore I do not wish to be limited to the above disclosure except as may be required by the 55 claims.

What I claim is:—

A cap provided with a vizor comprising a lower wall stitched across its top directly to the outer wall of the cap, and an upper 60 wall secured along the edges of said lower wall and terminating at the junction of said outer and lower walls to provide an open-mouth pocket for the ready insertion and removal of a stiffening member.

In testimony whereof, I affix my signature, in presence of two witnesses.

ARTHUR HALE.
